UNITED STATES PATENT OFFICE.

LOUIS E. ANDERSON, OF CHARLOTTE, NORTH CAROLINA.

WINDING ATTACHMENT FOR QUILLER FRAMES.

Application filed June 24, 1927. Serial No. 201,162.

This invention relates to improvements in quiller frames whereby the said frame may be used as a winding machine. Heretofore, I am aware that various types of winding machines have been used, but in the type known as the Universal winding machine there are ten bobbins on each side of the machine, and one operator is necessary to attend to four of such groups of ten, making 10 it necessary to have one operator for every forty bobbins. I am now speaking of the winding machines for winding silk and rayon. In the quiller frame of the type shown with my invention attached thereto 15 there are 378 bobbins, but this type of winding machine is used only for cotton and other fibres and cannot be used successfully for the winding of rayon and silk for the reason that there is not sufficient lap in the winding 20 to cause the silk and rayon fibres to remain wound on the bobbin.

It is an object of my invention to provide a mechanism which is adapted to be used on a quiller frame whereby one operator can attend to the whole machine, and thereby attend to 378 bobbins at one time, thus saving the services of more than eight employees for each of my improved machines which may be used.

Another object of my invention is to provide means adapted to be attached to a quiller frame for winding silk and rayon on a quiller frame.

Some of the objects of my invention having been stated, other objects will appear as the description proceeds, when taken in connection with the accompanying drawings, showing a preferred embodiment of my invention, a detailed description being herein- 40 after set forth, but immediately following is a brief description of the various figures in the drawings, in which

Figure 1 is a front elevation of a quiller frame showing my attachments mounted thereon, with the central portion of the frame being broken away;

Figure 2 is an end elevation of one end of my machine, showing the attachments;

Figure 3 is an elevation of the opposite 50 end of the quiller frame from Figure 2, showing the manner in which my attachments are mounted on the frame;

Figure 4 is an enlarged detail side elevation of a portion of the bobbins and the eyes 55 for feeding the thread to the bobbins;

Figure 5 is a plan view of the structure shown in Figure 4;

Figure 6 is a side elevation of one of the bobbins showing the arc travelled by the eyes 60 in my attachment;

Figure 7 is an enlarged detail view of a side elevation of the crank arms and associated parts;

Figure 8 is a view along the line 8—8 of 65 Figure 7;

Figure 9 is a view along the line 9—9 in Figure 7.

Referring more particularly to the drawings, the numeral 10 indicates one of the end standards of a quiller frame, and the numeral 11 indicates the other end of the quiller frame. These standards are secured to each other by the conventional bolster or spindle rails 12. These spindle rails have a plurality of bobbins 13 mounted for rotation thereon, 70 and in the type of quiller shown there are forty-two spindles mounted on each spindle rail, and the entire frame has nine tiers of these spindle rails, making a total of three hundred and seventy eight spindles in the 75 machine.

Located slightly above and adapted to have a vertical movement between the tiers of spindles are the guide wire rods 14 which are mounted for rotation in bearings 15 extending downward from the bars 16, said bars 16 being inclined, and are supported by the lifting rods 17 of the builder motion. The eye members 18, sometimes referred to as the guide wires, are securely mounted on 90 the guide wire rods 14, so that there is one eye for each bobbin to be wound. The spindles carrying the bobbins are driven in the conventional manner by a pulley and cord 19, the cord 19 running from one of the 95 drums (not shown) in the rear of the quiller frame.

To the right hand end of the guide wire rods 14 there are secured crank arms 20 which project upwardly and have their ends connected to a common bar member 21, and to this bar member 21 there is connected in a pivotal manner the connecting rod 22, which rod 22 is pivotally connected to the side of the wheel 23, the wheel 23 being fixedly secured to the rod 24. This rod 24 is rotatably mounted in bearings 25 located on the supports 26.

The power for driving the machine is derived from the belt 27 engaging the split 110

pulley 28, mounted on the shaft 29, and on the other end of this shaft 29 there is mounted the gear wheel 30 which wheel 30 is connected to the gear wheel 31 by means of the chain belt 32. The wheel 31 is fixedly mounted on the roll member 33 which is rotatably mounted in bearings in the upper portions of the standards 10 and 11, and near the standard 10 there is fixedly mounted on the 10 roll member 33 the gear wheel 34, which meshes with the gear wheel 35. The gear wheel 35 is mounted on the rotatable shaft 36 and a second gear wheel 37 is fixedly mounted on this shaft and on the outer side 15 of this gear wheel 37 there is eccentrically mounted the downwardly extending rod 38. On the end of the rod 24 nearest the standard 10 there is fixedly mounted the gear wheel 40, and on the standard 10 there is 20 mounted the tightening gear wheel 41, and a chain belt 42 passes over the wheels 37, 40 and 41.

The bearings 25 are slidably mounted on the rods 26, and in Figure 1 the whole frame 25 and the rod 24 are raised up out of operative position for sake of clearness, which renders the wheel 40 invisible, but the up and down movement of the builder motion is not present in this arrangement as in the conventional quiller frame where the guide wire rods have such up and down movement.

The rod 38 extends downwardly and is pivotally connected to one end of the lever 45, which lever is pivotally mounted near its center on the shaft 46, and fixedly secured on the shaft 46 is the gear wheel 47 which preferably had 120 teeth therein. The dog 48 is adapted to engage the teeth in this gear wheel 47 and thereby rotate the 40 shaft 46 one tooth at a time. The shaft 46 has a worm gear 49 thereon which engages with the other portion 50 of the worm gear member, and a chain member 51 passes from this member to the lever 52 which is pivoted 45 as at 53 and has weights 54 on one end thereof, and the other end of this lever presses against the bottom of the lifting rods 17. All of the parts in the above assembly are 50 conventional parts in a quiller frame except the rod 38, hence a further description is deemed unnecessary, as it is apparent that the up and down movement of the rod 38 will cause the lifting rods 17 to be pushed upwardly and the rods 14 will also be gradually raised upward.

The gradual raising of the frame holding the guide wire rods 14 which are supported by the inclined bars 16 is very much the same as in the ordinary quiller frame, the 60 ratcheting being done by the rod 38 and associated parts. In the ordinary quiller frame the guide wire rods 14 are not rotated but remain in a fixed position and are raised vertically while the spindles are being rotated. In my device I have the crank

arms 20 secured to one end of the wire guide rods, and when the machine is placed in motion the wheel 40 is rotated and the rod 24 on which the same is fixedly mounted is also rotated and the wheel 23 is also rotated, and by means of the connecting rod 22 the rod 21 is reciprocated and the wire guide rods 14 are given a partial revolution as shown by the dotted lines in Figure 6. In this way the thread is lapped on the 70 bobbins in such a manner as to cause this machine to be adaptable to be used as a winding machine for silk and rayon. In the use of this machine the silk or rayon is run direct from the creels over the roller 33 and 75 thru the eyes in the guide wires.

The crank arms 20 have longitudinally disposed slots 20^a therein and a bolt 20^b pierces this slot and also a hole in the rod 21, and in this way the position of the rod 85 21 is adjusted relative to the crank arms to regulate the length of arc of oscillation of the guide wires 18.

In the drawings and specification I have set forth a preferred embodiment of my invention, and although specific terms are employed, they are used in a generic and descriptive sense only, and not for purposes of limitation, the scope of the invention being set forth in the appended claims: 95

I claim:

1. A traversing device for quiller frames equipped with guide wire rods comprising arms secured to the guide wire rods, a rod connecting the arms together for unified 100 movement, and a reciprocating rod adapted to impart oscillatory movement to the guide wire rods.

2. A quiller frame having rectilinearly reciprocating means for imparting oscillatory 105 arcuate movement to the guide wire rods.

3. In a quiller frame equipped with guide wire rods, a frame for supporting the guide wire rods, a builder motion for the frame for supporting the guide wire rods, crank 110 members secured to the guide wire rods, a member for connecting the crank members together, a connecting rod adapted to be reciprocated by the power driving the machine, said connecting rod being pivotally connected to the member connecting the crank members, all of said members being adapted to impart oscillatory movement to the 115 guide wire rods.

4. A traversing device for quiller frames 120 equipped with guide wire rods comprising bearings for the guide wire rods, crank arms on the guide wire rods, a rod pivotally connected to each of the crank arms, a second rod pivotally mounted at one end thereof to the first rod, and having its other end pivotally connected to a wheel, said wheel being fixedly mounted on a rotatable shaft, and means connecting the rotatable shaft to a source of power, all of said parts being 125 130

adapted to impart oscillatory motion to the guide wires.

5. In a winding machine, a quiller frame having a builder motion and guide wire rods, means for imparting an oscillatory motion to the guide wire rods, and means for simultaneously raising the guide wire rods while the same are being oscillated.

6. In a quiller frame having a builder motion and guide wire rods, means for connecting all of the guide wire rods together for simultaneous oscillatory movement, a rotatable shaft driven by the movement of the machine, and means connected to the rotatable shaft and to the guide wire rods for imparting oscillatory movement to the guide wire rods.

7. A quiller frame having a builder motion, guide wire rods, guide wires, crank arms mounted on the ends of the guide wire rods, a member for connecting all of the crank arms together, a rotatable shaft mounted in the frame and having a wheel fixedly secured on the end thereof, a rod connected to the wheel and the member connecting the crank arms together, a gear wheel on the other end of the rotatable shaft, geared connections for imparting movement to the rotatable shaft, all of said parts being adapted to cooperate to impart oscillatory movement to the guide wire rods.

8. In a winding attachment for quiller frames, a gear wheel mounted on one of the standards of the frame and being in geared

connection with the top roll of the frame, a 35 downwardly extending rod eccentrically mounted on the gear wheel, the lower end of the rod being connected to the builder motion for operating the same, a rotatable shaft mounted in the upper portion of the 40 frame, a gear wheel on one end of the rotatable shaft, geared connections between the first and second gear wheels, the rotatable shaft having a wheel mounted thereon to rotate therewith, crank arms on the guide 45 wire rods, means for connecting all of the crank arms together for unified movement, and a rod connecting the wheel on the rotatable shaft with the crank arms, all of 50 said parts being adapted to cooperate to impart an oscillatory motion to the guide wire rods while the same are being elevated by the builder motion of the machine.

9. In an attachment for quiller frames, a plurality of inclined bars, a plurality of 55 guide wire rods mounted for oscillatory movement in the inclined bars, means for gradually raising the inclined bars and the guide wire rods, crank arms on the ends of the guide wire rods, means for connecting 60 the crank arms together for simultaneous movement, and means for imparting oscillatory movement to the guide wire rods while the same are being raised by the operation of the machine. 65

In testimony whereof I affix my signature.

LOUIS E. ANDERSON.
